(57) **CLAIM**

The ornamental design for a wig grip cap, as shown and described.

DESCRIPTION

FIG. 1 is a front, right, top perspective view of a wig grip cap, showing my new design;
FIG. 2 is a rear, left, bottom perspective view thereof;
FIG. 3 is an enlarged front elevational view of the wig grip cap;
FIG. 4 is an enlarged rear elevational view of the wig grip cap;
FIG. 5 is a left side view of the wig grip cap of FIG. 1;
FIG. 6 is a right side view thereof;
FIG. 7 is an enlarged top plan view of the wig grip cap;
FIG. 8 is an enlarged bottom plan view of the wig grip cap;
FIG. 9 is an enlarged view of the wig grip cap shown within the area designated as 9 in FIG. 1;
FIG. 10 is an enlarged view of the wig grip cap shown within the area designated as 10 in FIG. 1;
FIG. 11 is an enlarged view of the wig grip cap shown within the area designated as 11 in FIG. 1;
FIG. 12 is an enlarged view of the wig grip cap shown within the area designated as 12 in FIG. 2;
FIG. 13 is an enlarged view of the wig grip cap shown within the area designated as 13 in FIG. 2;
FIG. 14 is an enlarged view of the wig grip cap shown within the area designated as 14 in FIG. 2;
FIG. 15 is an enlarged view of the wig grip cap shown within the area designated as 15 in FIG. 3;
FIG. 16 is an enlarged view of the wig grip cap shown within the area designated as 16 in FIG. 3;
FIG. 17 is an enlarged view of the wig grip cap shown within the area designated as 17 in FIG. 4;
FIG. 18 is an enlarged view of the wig grip cap shown within the area designated as 18 in FIG. 5;
FIG. 19 is an enlarged view of the wig grip cap shown within the area designated as 19 in FIG. 5;
FIG. 20 is an enlarged view of the wig grip cap shown within the area designated as 20 in FIG. 7;
FIG. 21 is an enlarged view of the wig grip cap shown within the area designated as 21 in FIG. 8; and,
FIG. 22 is an enlarged view of the wig grip cap shown within the area designated as 22 in FIG. 8.
The broken lines shown in the drawings depict portions of the wig grip cap that form no part of the claimed design. The dash-dot-dash broken lines encircling portions of the wig grip cap are for identification purposes only.

(Continued)

grip cap in FIGS. 1-5, 7-8 and illustrated in the enlarged views in FIGS. 9-22 form no part of the claimed design.
